CLAIM

The ornamental design for a handle, as shown and described.

DESCRIPTION

FIG. 1 is an isometric view of a handle showing our new design;

FIG. 2 is a front elevation view thereof;

FIG. 3 is a rear rear elevation view thereof;

FIG. 4 is a top plan view thereof;

FIG. 5 is a bottom plan view thereof; and,

FIG. 6 is an enlarged right side elevation view thereof; the left side view being a mirror image thereof.

The even broken line showing the broken circle and the oval, the dash-dot-dash immediately adjacent the claimed areas represent the bounds of the claimed design while all other broken lines represent environmental structure and are for illustrative purposes only. None of the broken line or dash-dot-dash line form part of the claimed design.
